UNITED STATES PATENT OFFICE.

RUDOLF KNOLL, OF VIENNA, AUSTRIA-HUNGARY.

TELEPHONE-MOUTHPIECE.

No. 866,036.

Specification of Letters Patent.

Patented Sept. 17, 1907.

Application filed August 11, 1905. Serial No. 273,808.

To all whom it may concern:

Be it known that I, RUDOLF KNOLL, chemist, a citizen of the Empire of Austria-Hungary, residing at Vienna, Austria-Hungary, have invented certain new and useful Improvements in and Connected with Telephone-Mouthpieces, of which the following is a specification, reference being had therein to the accompanying drawing.

This invention relates to mouth pieces for telephones, and has for its object to provide an improved form of mouth piece device in which the mouth piece can be readily removed and replaced when desired; and which furthermore can be rotated to raise and lower the mouth piece to different elevations relative to the sound box or membrane chamber.

In the accompanying drawing, representing one embodiment of my invention, Figure 1 is a view partly in side elevation and partly in section of a sound box and portion of a mouth piece member. Fig. 2 is a similar view being wholly in side elevation; and Fig. 3 is an end elevation of the same, showing in the broken lines positions to which the mouth piece member can be rotated.

The diaphragm box *h* is provided with a short tube *k* externally threaded, the tube being connected with the sound box by a cover *g*. A spring member *a* is provided comprising a tube having one end internally threaded and screwed onto the threaded tube *k*. This member *a* is provided with a flange portion *c* and a tubular portion *d* containing slots *e*.

The mouth piece member *m* has a tube *n* suitably secured at one end which tube is provided with a flange *v*. The flange is bent inwardly at *r* and contains serrations forming a series of spring tongues as shown in Fig.

2. When the mouth piece is to be attached, the tube member *n* is slid on over the tube *d* of the diaphragm box, and the spring tongues of the flange *v* spring outward to pass the flange *c*, and then spring inward to

tightly grasp this flange and retain the mouth piece in position. The mouth piece is now seated rotatably and removably on the diaphragm box, and the elevation of the mouth piece can be raised or lowered by simply rotating the tube *m*. The mouth piece can be readily removed by pressure tending to spring outward the spring tongues of the flange *v*.

45

Having thus described my invention, I claim:

1. In a mouth piece for telephones, the combination with the diaphragm box and the mouth piece member, one of said members being provided with an annular flange and the other member being provided with spring tongues arranged to spring over the flange when the members are pressed together to rotatably support the mouth piece on the holder, one of the members also having a tubular portion having slots extending inwardly from its outer end, said tube being fitted into the other member to support 55 the same.

2. In a mouth piece for telephones, the combination with the diaphragm box of a tube secured thereto and provided with an annular flange, and also provided with a tubular portion projecting beyond the flange and having its extremity slotted, the mouth piece member being arranged to slide over the slotted tubular portion of the diaphragm box, and also provided with spring tongues arranged to spring over the annular flange of the diaphragm member to secure the mouth piece rotatably and removably 60 to the diaphragm member.

3. In a mouth piece for telephones, the combination with the diaphragm box of a tubular member screwed thereto and having its outer end slotted and provided with an annular flange at an intermediate portion, the mouth piece member being provided with a tubular portion arranged to slide over the slotted portion of said tube, and also provided with spring tongues arranged to spring over 70 said annular flange, whereby to removably and rotatably retain the mouth piece on the diaphragm member.

75

In testimony whereof I hereunto affix my signature in presence of two witnesses.

RUDOLF KNOLL.
